(57) **CLAIM**

The ornamental design for the vent cap device, as shown and described.

DESCRIPTION

FIG. 1 is a perspective view of one embodiment of our vent cap device looking at the exterior of our device.

FIG. 2 is a perspective view of the embodiment of our vent cap device shown in FIG. 1 looking at the interior of our device.

FIG. 3 is a top plan view of the embodiment of our vent cap device shown in FIG. 1.

FIG. 4 is a side elevation view of the embodiment of our vent cap device shown in FIG. 1; and,

FIG. 5 is a bottom plan view of the embodiment of our vent cap device shown in FIG. 1.
